(57) **CLAIM**

(**) Term: **14 Years**

The ornamental design for a docking station for connection to a notebook computer and extension to connection interfaces, as shown and described.

(21) Appl. No.: **29/188,444**

DESCRIPTION

(22) Filed: **Aug. 15, 2003**

FIG. 1 is a perspective view of a docking station for connection to a notebook computer and extension to connection interfaces showing the new design.

(51) LOC (8) Cl. **14-02**

FIG. 2 is a front view thereof.

(52) U.S. Cl. **D14/434**

FIG. 3 is a rear view thereof.

(58) Field of Search D14/432-4; 361/679-87;

FIG. 4 is a left side view thereof.

200/5 R, 5 A, 6 R, 6 A

FIG. 5 is a right side view thereof.

D359,034 S * 6/1995 Kondo D14/434

FIG. 6 is a top view thereof; and,

D396,705 S * 8/1998 Iino D14/434

FIG. 7 is a bottom view thereof.

D400,515 S * 11/1998 Shima D14/433

The features shown in broken lines in the rear view and the bottom view are shown for illustrative purposes only and form no part of the claimed design.
